CHAISE LONGUE

James E. Jones, Toledo, Ohio, assignor to The Hetrick Manufacturing Company, Toledo, Ohio, a corporation of Ohio

Application March 14, 1956, Serial No. 40,612

Term of patent 14 years

(Cl. D15—11)

I claim:

The ornamental design for a chaise longue, as shown.
